(57) **CLAIM**

The ornamental design for a display screen with graphical user interface, as shown and described.

DESCRIPTION

FIG. 1 is the first image in a sequence for a display screen with graphical user interface showing our new design; and, FIG. 2 is the second image thereof.

The appearance of the transitional image sequentially transitions between the first image and the second image shown. The process or period in which one image transitions to another image forms no part of the claimed design. The broken lines showing a display screen illustrate portions of the article that form no part of the claimed design.
